(57) **CLAIM**

The ornamental design image for a digital camera, as shown and described.

DESCRIPTION

FIG. 1 is a rear perspective view of an image for a digital camera;

FIG. 2 is a front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side view thereof; and,

FIG. 8 is a left side view thereof.

The broken line drawing of a digital camera in all views is for illustrative purposes only and forms no part of the claimed design.
